[57] **CLAIM**

I claim the ornamental design for the roll towel dispenser
with transparent cover, as shown and described.

DESCRIPTION

FIG. 1 is a right front perspective view of the roll towel
dispenser with transparent cover showing my new design;
FIG. 2 is a front elevation thereof;
FIG. 3 is a rear elevation thereof;
FIG. 4 is a top plan view thereof;
FIG. 5 is a bottom plan view thereof;
FIG. 6 is a right side elevation thereof;
FIG. 7 is a left side elevation thereof.
